UNITED STATES PATENT OFFICE.

LEE HOWARD SIMMONS, OF GOLDSBORO, NORTH CAROLINA, ASSIGNOR TO SIMMONS MANUFACTURING COMPANY, OF WILMINGTON, NORTH CAROLINA, A CORPORATION OF NORTH CAROLINA.

GRATE.

Application filed June 21, 1921. Serial No. 473,193.

To all whom it may concern:

Be it known that LEE HOWARD SIMMONS, a citizen of the United States, residing at Goldsboro, in the county of Wayne and State of North Carolina, has invented certain new and useful Improvements in Grates, of which the following is a specification.

My invention relates to a new and useful improvement in grates for stationary or locomotive boilers, and in the present drawings I have shown the grate as embodied in a locomotive, although it may be equally as well applied under any stationary boiler.

In its broadest aspect it is somewhat similar in type to the grate shown in Patent No. 1,321,252, granted to me Nov. 11, 1919, and to the grate shown in the application filed by me on Oct. 4, 1920, bearing Serial No. 414,588.

20 In both the patent and the application above mentioned however, the small grate or fire bars are actuated by a rocker bar, while in the present instance, as will be hereinafter more fully described, the grate or fire bars 25 though easily inserted or removed are not actuated by the rocker bar, but are designed to rock or tilt only when the frames supporting these bars, are actuated to dump the fire.

One of the numerous objects of my invention is to provide a grate which is to be 30 made up of a plurality of sections or frames so that the grate area may be of the desired size depending on the size of the boiler.

Another object of my invention is to provide a grate, the frames of which may be 35 rocked by a small power-operated means of the ordinary type used in connection with locomotive grates if the grate is installed in a locomotive, or may be rocked by any preferred automatic means if installed under 40 a stationary boiler, and is also arranged to be rocked manually should it be desired or necessary.

Still another object of my invention is to 45 provide in a grate, a plurality of frames on which there are provided a plurality of small quickly removable fire bars, so that it is a simple matter to replace any of them when they become damaged by continuous use.

50 Still another object of my invention is to provide a clinker breaking means that is to

be located in each of the grate frames so that the fire bed may always be kept in as near a perfect condition as possible.

As it is well known to those skilled in the art, large clinkers are bound to form in the fire bed which retard the efficiency of any grate, and which have to be removed, generally by means of an operator with a slice bar. The present invention therefore contemplates the breaking up of these clinkers while they are in a molten state and before becoming hardened.

Still another object of the invention is to provide a grate wherein the grate or fire bars are held in a locked position after being inserted but may be quickly removed or replaced when desired.

Still another object of my invention is to provide a grate wherein all but two of the frames supporting the fire bars may be rocked in unison when it is desired to dump the fire.

Still another object of my invention is to so form the grate that the fire bed may be 75 quickly agitated by the clinker breakers to keep the fire bed in its highest efficiency, and to also form the grate so that the grate frames, with the fire bars and clinker breakers may be rocked when it is desired 80 to dump the fire.

Still another object of the invention is to so arrange the clinker breakers and their means of support, that it will be impossible for the clinker breakers to remain in their 85 uppermost or operated position. This is desirable as if the arrangement was not such, the clinker breakers might be left in a raised position, extended into the fire bed, and they would soon melt or be destroyed by the heat. 90

Still another object of the invention is to arrange all of the clinker breakers with the exception of those next to the rear wall to actuate in one direction that is, towards the front of the fire bed, while those in the last 95 two frames are designed to swing toward the rear end of the fire bed.

In most of the grates now installed in locomotives it is necessary to provide long rakes or slice bars, so that the clinkers and 100 the fire bed next to the crown sheet may be raked, agitated or cleaned out, as no auto-

matic means are provided, and the fire bed is generally poor at this point, thereby lowering the efficiency of the grate, and not securing the maximum heat from the coal burned.

Still another object of my invention is to provide means for rocking the clinker breakers in the two front frames, which means are actuated independently of the means operating the remaining clinker breakers.

Still another object of my invention is to provide a grate especially adapted for use in a locomotive comprising a plurality of tiltable or rocking grate frames having two frames at the front end of the grate that are stationary.

With these and numerous other objects in view, which will be hereinafter more fully described as the specification proceeds, my invention consists in certain new and novel constructions and combination of parts as will hereinafter be more fully described and pointed out in the claims.

Referring now to the drawings which show a preferred form of the invention;

Fig. 1 is a plan view of my improved grate partly in section and parts removed for clearness of illustration.

Fig. 2 is a vertical sectional view substantially on line 2—2 of Fig. 1 showing the different parts in a normal position.

Fig. 3 is a similar view taken on a line with the center rest bar, a number of parts being removed for the sake of clearness and showing a part of three grate frames in section and in their normal position.

Fig. 4 is a view at the far side of the grate showing a side rest bar composed of two sections.

Fig. 5 is a cross sectional view on line 5—5 of Fig. 1.

Fig. 6 is an enlarged fragmentary sectional detail view showing two of the rocking frames and a stationary frame in their normal position, the clinker breakers however in all of their frames in their operated position.

Fig. 7 is a similar view showing the rocking frames in a tilted or rocked position the clinker breakers being in their normal position.

Fig. 8 is a front elevation showing the means for operating the different parts of the grate some parts being shown in section for the sake of clearness.

Fig. 9 is a side elevation of a fire or grate bar and

Fig. 10 is a similar view of a clinker breaker.

It is to be understood at the outset that throughout the specification and the claims the terms "front and rear" are used with the assumption that the grate is installed in a locomotive and the front end of the grate

being positioned near the front of the locomotive. This is also followed with regard to the front and rear walls of the grate frames.

It might also here be mentioned that the grate may be advantageously used under stationary boilers as well as under locomotive boilers.

In Fig. 1 of the drawings, two side walls 1 are shown, and the front wall 3 and the rear sheet 2. A center rest bar 4 is shown for supporting the adjacent ends of the grate frames, this center bar being the subject matter of a separate application filed by me in the United States Patent Office on March 21, 1921 and bearing Serial No. 454, 80 135, Patent No. 1,416,131.

Suitable supports or brackets 5 and 6 (Fig. 2) are shown for holding this center rest bar while spaced along the side walls 1 are the side rest bars 7, which may be in two parts as shown in Fig. 4, or might be one continuous bar if desired.

Lugs 8 are spaced along the walls for properly supporting the side rest bars 7 which bars are provided with a plurality of 90 downwardly extending projections 9 which are in turn provided with the trunnions 10 for pivotally supporting the grate frames, which frames will hereinafter be described in detail.

It is to be noticed that at the forward end of the side rest bars 7 there are two projections 11 provided with the trunnions 12, and on the center rest bar the trunnions 13 are provided with two trunnions 14 corresponding to the trunnions at the forward ends of the side rest bars 7.

In the rear wall under the cab floor there are shown two openings 15 through which the ends of the grate operating connections 105 are passed, which connections will also be mentioned more in detail.

Just below the cab floor there is provided a bracket 16 on which there will be placed a power operating means C of the ordinary type now used on locomotives, which in the present instance is designed to operate a portion of the grate mechanism, and in the present instance this means C is shown mostly in outline for the sake of illustration only, as any other form of suitable power operating means may be employed.

A small connecting link 18 will be seen and two air connections 19 which will be properly connected with the air or a steam pressure 120 line.

Located slightly above the operating means C is a hanger 20 in which is mounted the shaft 21 on the outer end of which is the arm 22 which is to be operated through 125 the connecting link 18.

An upright arm 23 is rigidly fastened centrally of this shaft 21 and on its outer

end is secured two oppositely positioned latch members 24.

Any movement or rocking of the shaft 21 will therefore likewise rock the arm 23 with the latch members thereon which members are designed to engage either of two of the operating levers, as will hereafter be mentioned.

Grate frames.

10 Referring now to the grate frames that are to be mounted on the center and side rest bars it will be clearly seen from Fig. 1 that twelve are shown, two of which are 15 rigidly mounted while the remainder are pivotally mounted and capable of being rocked to dump the fire as will later be described in detail.

It is also to be noted that the present grate 20 comprises two complete series or units A and B, consisting of six frames each and as each unit is identical and has identical operating mechanism, a description of the one will suffice.

25 The tiltable grate frames 25 are rectangular in shape consisting of the side walls 27, the rear wall 28 and the front wall 29. The stationary grate frame 26 is slightly smaller and consists of the rear wall 28', front wall 30 29' and side walls 30. On each of the tiltable frames 25 there is shown a yoke 31 which is preferably cast integral with the frame and extends from the under surface from the front and rear walls. On the lower 35 portion of this yoke is the lug 32 so that an operating bar may be secured thereto.

This yoke not only forms a member to which the operating bar may be conveniently secured but also greatly strengthens the entire frame. The side walls 27 of each frame 40 25 are provided with cut out portions 33 on their under side to provide bearings so that the frames may be pivotally supported on the heretofore mentioned trunnions 10 and 45 13 of the side and center rest bars.

It is to be noticed that this bearing 33 is formed to one side of the center of the side walls.

Each of the tiltable frames 25 is provided on the inner surface of their rear walls 50 with a small flange 34 that is slightly below the upper surface of the frame, while a flange 35 having a notch 35' is formed on the inner surface of the front wall of each 55 frame, and in this instance the upper surface of the flange lies in a plane with the surface of the front wall.

The stationary frame 26 is also provided with two similar flanges 36 and 37, in this instance, however the position of the flanges being just reversed as the entire grate frame and all of its parts are in a reversed position to the tiltable frames.

The stationary frame is also provided 60 65 with two bearings or cut out portions 38 on

the under surface of each of its side walls so that this frame will be rigidly mounted on the aforementioned trunnions 12 and 14 of the center and side rest bars.

Each of the side walls 27 of the tiltable 70 frames 25 is provided near its upper surface with the cut-outs or bearings 40 while the stationary frame has similar bearings 41 in the upper portion of its side walls, the purpose of the same being for the reception of 75 means for supporting and operating the clinker breakers, which will be shortly described.

So that the rocking frames may be operated simultaneously, a bar 42 is shown which 80 is connected to the lugs 32 on the yokes 31 and for operating this bar 42 there is provided a rod 43 connected thereto which extends through the aforementioned opening 15 and is connected to the lower end of a 85 lever 44 which is freely mounted on the shaft 21 as this lever 44 is to be operated manually.

Fire or grate bars.

As heretofore mentioned each of the grate frames is provided with a plurality of grate or fire bars 45 which extend slightly beyond the front and rear walls of the frames and rest thereon.

Fig. 9 shows in detail one of these fire bars and it might be here mentioned, that the fire bars in both the stationary and tiltable frames are identical except as to dimensions and that the stationary frame and the fire 100 bars are in a position reversed to that of the rocking frame.

Each fire or grate bar is of relatively small transverse thickness (see Fig. 1) so that a number of them may be located in each 105 frame. On the under portion of the bar are the two oppositely positioned depending lugs 46 and 47, lug 46 being notched as at 48 and lug 47 being notched as at 49, the bearing surfaces 50 extending out beyond the two 110 lugs.

The purposes of these notches 48 and 49 being to co-operate with the two flanges 34 and 35 on the inner surfaces of the front and rear walls of the grate frame.

As before mentioned the flange 35 of each frame is provided with a notch 35' so that one end of the fire or grate bar may be placed over this notch and the fire bar dropped in place, the other end of the fire bar with the 115 notch portion 48 being first placed below the flange 34. The bar is then moved transversely of the frame the two notches in the lugs co-operating with the aforementioned flanges thereby locking the fire bar in place 120 so that it cannot become accidentally disengaged or dropped from the frames when moved to its rocked position.

Two spacing lugs 51 are shown on the one side of the grate or fire bar which lugs are 130

adapted to contact with the adjacent bar so that all of the bars will be in a slightly spaced relation to each other.

As shown in Fig. 5, at the opposite extremities of the frame, fire bars 52 are provided which are of approximately twice the thickness of the other fire bars. This is to provide means for preserving the side walls of the frames from the heat, as of course it is much easier and cheaper to supply even double thick fire bars than to provide a whole new frame.

When one of these fire or grate bars becomes damaged or cracked in service, it should be knocked with a hammer from the frame and a new one inserted as heretofore explained.

By providing a plurality of these narrow fire bars the cost of replacing them is far less than the cost of a heavy ordinary form of grate bar.

Clinker breakers and their operating means.

For agitating or raking the fire bed and for preventing the forming of clinkers and for breaking up the clinkers while still in molten state a plurality of clinker breakers 53 are used. Each clinker breaker consists of a body 54, a shank portion 55 and a head portion 55' disposed transversely of the shank as clearly shown in Fig. 10. The outer end of the shank is enlarged as at 56 and is provided with a rectangular opening 57 having an entering slot 58. A boss 59 is provided around the opening to strengthen the clinker breaker at this point. The head 55' is curved or cut out along its one edge as at 60 so that when in its normal position in the grate frame, a space 61 (Fig. 2) will be left between it and the lower edges of the two adjacent grate bars. This permits any ashes that collect on the edge 60 to fall therefrom and permits a circulation of the air between the clinker breaker and the fire bars which will tend to keep the clinker breaker in a cooler condition.

As will be seen in Fig. 10 the body portion extends downwardly as at 62 so that the distribution of the weight of the clinker breaker, will together with the way it is mounted, permit it to fall back to its normal position after being operated. Also by providing the clinker breaker with this downwardly extending portion it is impossible for the lower end of the clinker breaker to extend above the upper surface of the fire bars, which action would cause the clinker breakers to jam with the coal or ashes of the fire bed and they could not be returned to their normal position.

These clinker breakers 53 are mounted on a shaft 63 which is provided with the trunnions 64 at its opposite ends (Fig. 5), which trunnions are designed to fit or rest within the afore mentioned bearings 40 of the tilt-

able frames 25 or in the bearings 41 of the stationary frames 26. These rocker bars 63 each consist of a body or web 65 on which is formed the enlarged head 66, the shape of the head corresponding to the opening 57 in the clinker breaker and the thickness of the web 65 corresponding to the width of the entrance 58 of the clinker breaker so that the clinker breaker when once placed in position will be locked with relation to the rocker bar. The head 66 of each rocker bar is notched at two points as at 67 (see Fig. 1), so that the clinker breaker may be easily placed on the rocker bar and then moved transversely thereof to a locked position.

Should one of these clinkers breakers become broken or damaged by the heat it may also be knocked from the rocker bar and a new one inserted and moved along to a desired position.

Any desired number of these clinker breakers may be used and in practice I have found that one placed between every three or four fire bars is sufficient for a successful operation of the grate.

On the body portion 65 of the rocker bar may be formed a strengthening lug 68 and cast integral therewith is an arm 69 having a pin 70 near its lower end so that a bar 71 may be conveniently connected thereto.

As will be seen this bar 71 connects with the arm 69 of each of the rocker bars 63 of the tiltable frames 25 so that when this bar 71 is operated it will rock every one of the rocker bars 63 simultaneously.

By providing the trunnions 64 and the pivotal points or bearings as heretofore mentioned in the frames, a movement of these rocker bars will cause the clinker breakers to assume the position, in the tiltable frames as shown in Fig. 6, that is, the heads 55' of the clinker breakers will extend above the surface of the fire bars and up into the fire bed. A few operations at frequent intervals of these clinker breakers will keep the clinkers from forming and thoroughly rake the fire.

For operating this bar 71 a further bar or rod 73 is connected thereto as clearly shown in Fig. 2, while the rear end of this bar 73 is connected to the lever 74 mounted on the aforementioned shaft 21. This lever 74 will be engaged, when desired to operate the clinker breakers, by the aforementioned latch 24 mounted on the arm 23.

In the stationary grate frame 26 there is also a rocker arm 75 similar to the rocker arm 63 except as to size, and on which there is mounted a plurality of similar clinker breakers 76. To operate this rocker arm and these clinker breakers a separate connecting rod 77 is shown which is connected at its rear end to the lever 78 which is also mounted on the afore-mentioned shaft 21.

It is to be noticed however, that the rocker

arm and clinker breakers in this stationary frame operate in the opposite direction to those in the frames 25, the clinker breakers thus swinging towards the rear of the grate 5 and towards the tilttable frame.

It is at this point at the front end that an ordinary grate generally becomes congested and chokes up the throat due to its distance from the fire door and its inaccessibility.

10 By using the above described means the throat may be kept clean at all times, the clinker breakers thoroughly raking the fire bed and breaking up the clinkers at this point.

15 From the above description it will be seen that when it is desired to rake or agitate the fire bed it is only necessary to move the lever 74 so that it is engaged by the latch member 24 which is mounted on the 20 end of the arm 23 and admit the air or steam into the power operating means C.

In the drawings I have not shown a handle in connection with the lever 74 but one may of course be provided so that if it 25 should become necessary to operate the clinker breakers by hand it could easily be done.

The movement of the above mentioned lever forwardly and rearwardly will cause 30 a simultaneous movement of the rocker arms and the clinker breakers mounted thereon to extend or swing upwardly into the fire bed and again to their normal position, the upward movement thoroughly raking the fire bed and breaking up the molten clinkers. 35 This operation of the clinker breakers should be carried out at frequent intervals so that the clinkers in the mean time will not have a chance to completely harden.

40 The other lever 78 will then be swung over and be engaged by the latch 24 and the power operating means again started so that the clinker breakers in the stationary frame operate, and in this instance they 45 swinging on their upward movement towards the above mentioned clinker breakers.

When it is desired to drop or dump the fire it is only necessary for the fireman to 50 operate the lever 44 which as remembered is connected through a rod and a bar to the yokes of all the tilttable frames.

A few movements of this lever causing 55 all the tilttable frames to rock will dump the fire in a relatively short time. The clinker breakers in the stationary grate may then be operated if desired while the tilttable frames are in the rocked position which will entirely clean the grate.

60 As heretofore mentioned the grate consists of two complete units and the foregoing operations would of course apply to both series, or units.

From the foregoing it will be seen that

the grate possesses a number of advantages. 65 In the first place the fire can be easily and quickly dropped or dumped, which is highly desirable in a locomotive grate. Again, by providing the clinker breakers and their means of support and operation the fire is 70 kept at a high point of efficiency, as the fire bed may be continually raked and the clinkers broken up while in their molten state. Also by having the stationary grate frames at the forward end of the grate with 75 the clinker breakers positioned to swing towards the rear of the grate, the "throat" may be kept in a clean condition which, as far as I am aware is not possible with the 80 grates installed in locomotives today.

Also the grate is one that is relatively economical both in first cost and maintenance, as the only parts that are subjected to the great heat are the relatively small and inexpensive fire or grate bars which 85 may be quickly renewed as necessary.

Many slight changes may be made in the grate or in the levers operating the different parts of the grate without in any way departing from the spirit and scope of the 90 invention.

Having described the invention what is claimed is:—

1. A grate comprising a support, grate frames pivotally mounted upon the support, 95 means for rocking the grate frames simultaneously, grate bars detachably mounted upon the frames, clinker breakers pivotally mounted upon the grate frames and means for rocking the clinker breakers simultaneously. 100

2. A grate comprising a support, grate frames pivotally mounted upon the support, means for rocking the grate frames simultaneously, grate bars detachably mounted 105 upon the frames, clinker breakers pivotally and detachably mounted upon the grate frames and means for rocking the clinker breakers simultaneously.

3. In a grate, a grate frame having spaced 110 side portions, a yoke connected with the side portions, rocking means connected with the yoke, fire bars detachably mounted upon the side portions and bridging the space between the side portions, said fire bars being spaced from each other and clinker breakers supported upon the frames and lying in the spaces between the fire bars. 115

4. A grate comprising a support, a series 120 of grate frames pivotally mounted upon the support and normally lying in a plane inclined with relation to a horizontal line, means for rocking the grate frames simultaneously, clinker breakers pivotally mounted upon said grate frames, means for rocking the clinker breakers simultaneously toward the lower edge of the series of pivoted 125 grate frames, a single grate frame mounted

in a fixed position at the lower edge of the inclined grate frames, clinker breakers mounted upon the fixed grate frame and means for rocking the last mentioned clinker breakers toward the lower edge of the series of pivoted grate frames.

5. A grate comprising a support, grate frames pivotally mounted thereon and lying in inclined position, grate bars mounted upon the frames, clinker breakers pivotally mounted upon the grate frame, means for rocking the clinker breakers simultaneously in a direction toward the lower sides of the grate frames, a single grate frame mounted 10 in a position upon the support, clinker breakers mounted upon the fixed grate frame and means for rocking the last men- 15

tioned clinker breakers toward the lower side of the lower pivoted grate frame.

6. A grate comprising a support, grate frames pivotally mounted thereon and normally lying in inclined position, clinker breakers pivotally mounted upon said grate frames, means for rocking the clinker breakers toward the lower sides of the grate frames, a single grate frame mounted in a fixed position upon the support, and disposed in a horizontal position, clinker breakers movably mounted upon the fixed grate frame and means for rocking the last mentioned clinker breakers toward the lower side of the lower inclined grate frame.

In testimony whereof I affix my signature.

LEE HOWARD SIMMONS.
